United States Patent Office

Des. 210,795
Patented Apr. 16, 1968

210,795

INSULATED ICE CHEST OR SIMILAR ARTICLE

Jordan Birger and Marvin Birger, Newton, and Michael J. Di Pierro, Shrewsbury, Mass., assignors to Standard Oil Company, Chicago, Ill., a corporation of Indiana

Filed May 18, 1967, Ser. No. 7,171

Term of patent 14 years

(Cl. D44—1)

Fig. 1

Fig. 2

Fig. 3

FIGURE 1 is a perspective view of an insulated ice chest or similar article embodying our new design.

FIGURE 2 is a side view of an insulated ice chest or similar article embodying our new design.

FIGURE 3 is an end view of an insulated ice chest or similar article embodying our new design.

The dominant features of our design reside in the portion shown in solid lines in the drawings, handles being shown in broken lines.

We claim:

The ornamental design for an insulated ice chest or similar article, as shown and described.
